ASH TRAY

Boris Blecher, Philadelphia, Pa.

Application February 15, 1952, Serial No. 18,534

Term of patent 14 years

(Cl. D85—2)

To all whom it may concern:

Be it known that I, Boris Blecher, a citizen of the United States and a resident of Philadelphia, county of Philadelphia, State of Pennsylvania, have invented a new, original, and ornamental Design for an Ash Tray, of which the following is a specification, reference being had to the accompanying drawings, forming a part thereof, wherein:

Figure 1 is a plan view of the ash tray showing my new design;

Figure 2 is a side edge elevational view thereof as viewed from the line 2—2 of Figure 1;

Figure 3 is a transverse sectional view thereof as taken along the line 3—3 of Figure 1;

Figure 4 is a transverse sectional view as taken along the line 4—4 of Figure 1; and

Figure 5 is a transverse sectional view taken along the line 5—5 of Figure 1.

I claim:

The ornamental design for an ash tray, as shown.

BORIS BLECHER.
